CLAIM

The ornamental design for an underwater viewer, as shown and described.

DESCRIPTION

FIG. 1 is a front elevational view of an underwater viewer, showing my new design;

FIG. 2 is a side elevational view, the opposite side being a mirror image thereof;

FIG. 3 is a rear elevational view;

FIG. 4 is a top plan view; and

FIG. 5 is a bottom plan view.

FIG 1

FIG 2

FIG 3

FIG 4

FIG 5
